CARTRIDGE TYPE CIRCUIT BREAKER

James H. Burnside, 2nd, New York, N. Y., assignor, by mesne assignments, to Circuit Breakers, Inc., New York, N. Y., a corporation of New York

Application February 8, 1937, Serial No. 124,573
Renewed July 26, 1939

12 Claims. (Cl. 200—116)

The present invention relates to circuit breakers and embodies, more particularly, an improved form of circuit breaker which is adapted to be used in a manner similar to the cartridge type fuse, the construction of the breaker being such as to enable it to be used interchangeably with fuses of the above character. The structure in which the present invention has been embodied, accordingly, will be termed herein a "cartridge type" circuit breaker.

In circuit breakers of any type, it is a well known fact that the length of the gap between the contacts when opened is one of the factors which enters into the ability of the circuit breaker to successfully break currents of relatively high amperage and, accordingly, considerable attention has been addressed, heretofore, to this factor in the design of circuit breakers. Where the circuit breaker is small, this factor becomes the principal limiting factor in determining the rating of the circuit breaker.

With a view to providing a circuit breaker which is adapted to be built in small sizes and which is capable of breaking relatively large currents, the present invention has been designed, and an object of the invention is to provide a mechanism of this character which is able to interrupt relatively large currents without destructive arcing in the mechanism.

A further object of the invention is to provide a circuit breaker of the cartridge type wherein the movable breaker element is effectively controlled and of such character that relatively large currents may be interrupted effectively and without occasioning destructive arcing.

A further object of the invention is to provide a circuit breaker of the above character wherein the movable breaker element is operated through a free tripping mechanism by means of which manual actuation of the movable element is prevented when the circuit through the breaker is established.

A further object of the invention is to provide a circuit breaker of the above character wherein the releasing mechanism is so positioned as not to be exposed to any arcing which takes place upon the initial opening movement of the movable breaker element.

A further object of the invention is to provide a circuit breaker of the above character wherein the movable breaker element is controlled by a thermal mechanism which is of such character as to enable the thermal element to be extremely sensitive to all values of current flowing therethrough.

A further object of the invention is to provide a circuit breaker of the above character wherein the construction is such that the effective length of gap between the breaker contacts is increased by reason of the fact that the movable element is in series with two spaced stationary contacts.

Further objects of the invention will be apparent as it is described in further detail in connection with the accompanying drawings, where-
in

Figure 1 is a view in longitudinal section drawn on line 1—1 of Figure 2 and looking in the direction of the arrows, this view showing a circuit breaker of the cartridge type embodied in the present invention.

Figure 2 is a view in transverse section taken on line 2—2 of Figure 1 and looking in the direction of the arrows.

Figure 3 is a partial sectional view taken on line 3—3 of Figure 1 and looking in the direction of the arrows.

Figure 4 is a view in section taken on line 4—4 of Figure 1 and looking in the direction of the arrows.

Figure 5 is a view similar to Figure 1, showing the breaker contacts in open position.

Figure 6 is a detail view showing the thermal release mechanism of the device shown in Figure 1.

Figure 7 is a view in side elevation of the ele-
ments shown in Figure 6.

Figure 8 is a view in section, taken on line 8—8 of Figure 7 and looking in the direction of the arrows.

Referring to the above drawings, a circuit breaker of the cartridge type is shown as provided with spaced ferrules 10 and 11, having end walls 12 and 13, respectively, which close the ends thereof. Within the ferrules 10 and 11 a cylindrical tube 14 of insulating material is pro-
vided. The ferrules are secured fixedly to this tube and thus constitute therewith a unitary assembly.

The tube 14 is formed with a central hollow portion 15 as shown at Figures 1, 2, 4 and 5, this hollow portion being of irregular shape. The irregular shape of the hollow portion 15 is produced by four longitudinal splines or ridges 16 (Figure 2) which form side grooves 17 and 18 (Figures 2 and 4) and top and bottom grooves 19 and 20 respectively (Figures 1 and 2).

The side grooves 17 and 18 are adapted to receive the respective stationary contacts 21 and 22, contact 21 being connected to ferrule 10 by means of a contacting strip 23. Each of the sta-

tionary contacts 21 and 22 is received within recesses 24 which are formed within the grooves 17 and 18 in order that the contacting surfaces thereof may lie flush with the surfaces of such grooves. In order to permit the flaring stationary contact members to be inserted in the position illustrated in Figure 2, liners 24' are inserted endwise into the position shown in Figure 4, the cross section of these liners being the same as that of the stationary contacts. The manner in which stationary contact 22 is connected in the circuit will be described hereinafter.

Centrally of the tube 14 is an inner tube 25 which is formed with upper and lower splines 26, extending into the respective grooves 18 and 20. The inner tube 25 is slotted at 27 in each of the splines 26 in order that a pin 28 may be slidably received therein. The inner tube 25 is formed with a cylindrical hollow portion 29 axially thereof in order that a plug 30 may be slidably received therein. Plug 30 is secured to the pin 28 as will be readily apparent in Figure 1. A spring 31 is seated against end wall 12 of ferrule 10 and normally urges the plug 30 to the right as viewed in Figure 1.

About the outer periphery of the inner tube 25 there is provided a contact ring 32 which is slidably mounted with respect to the outer tube 14 and the inner tube 25. This contact ring is formed with upper and lower fan tail portions 33 which are received within the respective grooves 18 and 20 of the outer tube and slide upon the upper and lower splines 26 of the inner tube. The contact ring is also formed with lateral contact members 34 and 35 which slide in the respective grooves 17 and 18 and cooperate with the respective stationary contacts 21 and 22 to establish contact therebetween when the elements are in the position shown in Figure 1. The contacts 34 and 35 are provided with graphite inserts 36 upon the ends thereof where the electrical circuit is broken, these inserts cooperating with stationary inserts 37 on the respective stationary contacts 21 and 22 in order that destructive arcing may be avoided.

Inasmuch as the contact ring 32 is secured to the pin 28, spring 31 serves as a means for opening the circuit between the stationary contacts. Motion of the pin 28 to the left, as viewed in Figure 1, is effected by means of a manually operated slide member 38 which is provided at the ends thereof with finger members 39. The slide 38 is received within slots 40, formed in the upper portion of the tube 14. Within the upper portion 55 of tube 14 there is provided a hollow portion 41 which communicates with the upper slot 19. A leaf spring 42 is secured to the slide 38 and is formed with an aperture 43 within which the upper end of pin 28 is adapted to be received. The spring 42 is formed with a rounded nose 44 which facilitates the riding over and engagement of the spring 42 with the pin 28, in which condition the pin 28 may be advanced to the left, as viewed in Figure 1 and against the action of the spring 31.

The pin 28 is held in the closed position shown in Figure 1 by means of a bimetallic latch band 45 which is secured to the outer tube 14 by means of rivets 46 and at the end of the hollow portion 70 41 adjacent the stationary contacts 21 and 22. The end of the bimetal element 45 is formed with spaced fingers 47 which are adapted to engage recesses 48 formed in the upper end of pin 28. In order that the fingers 47 may secure the pin in the positions shown, the recesses 48 are formed

with detents 49 having sloping cam faces 50 in order that the fingers 47 may ride upwardly thereon and snap into engagement behind the detents 49.

In order that the connection between the spring 42 and pin 28 may be broken when the circuit is established to provide for a free tripping operation, the spring 42 rides up a cam surface 51 and is disengaged from the pin 28 after the fingers 47 have engaged behind the detents 49. At this instant the electrical circuit has not yet been established by reason of the fact that the circuit from the other stationary contact 22 to the ferrule 11 includes a sliding contact member 52 which is carried by the manually slideable member 38. This sliding contact member 52 rides upon a contact strip 53 which is in contact with the end ferrule 11 and engages the upwardly extending end 54 of the bimetal member 45 only after the spring 42 has disengaged the pin 28. The circuit 20 between the bimetal member 45 and the stationary contact 22 is established by means of a pigtail connection 55.

When the circuit is closed by means of the above construction, current flows between ferrules 10 and 11 through the contact strip 53 which is connected to ferrule 10, stationary contact 21, movable contact 34, contact ring 32, movable contact 35, stationary contact 22, pigtail 55, bimetal element 45, extension 54 thereof, sliding contact member 52 and contact strip 53 to the ferrule 11. Upon breaking the circuit by reason of a predetermined current flow through the bimetal element 45, the parting of the movable contacts 34 and 35 from the respective stationary contacts 21 and 22 thus breaks the circuit at two points dividing the resulting arc between the respective graphite inserts 36 and 37 which are mounted upon the respective movable and stationary contacts. Inasmuch as the spring 31 is received within the inner tube 25 and the slots 27 in such tube are angularly spaced 90° with respect to the contact members, any destructive effect of the arc upon the spring is reduced to a minimum. Moreover, the inner tube 25 effectively spaces the respective contacts 45 to prevent arcing over during the opening of the breaker. The foregoing construction enables the greatest portion of the length of the device to be utilized in breaking the circuit inasmuch as the movable contacts move with the pin 28 which moves practically to the end of the device. In order that the sliding contacts 52 may be urged against the contact strip 53 and bimetal end 54 effectively, the left hand end of spring 42 is extended upwardly to form a spring member 56 which engages against the stationary tube 14 as will be readily seen in Figure 1.

I claim:

1. A circuit breaker comprising an elongated insulating member having a terminal at each end thereof, spaced stationary breaker contacts within the said member adjacent one end thereof, means to connect one of said contacts to the adjacent terminal, a movable contact member, means to urge the movable member into an open position, means to hold the movable member releasably in a closed position, means to release the holding means, means connecting the other of the said stationary contacts to the other terminal, and means in the last named connection to actuate the releasing means upon existence of an excess current.

2. A circuit breaker comprising an elongated insulating member having a terminal at each

end thereof, said member being hollow and having spaced contacts formed therein adjacent one end thereof, means to connect one of the contacts to the adjacent terminal, an insulating tube

5 within the first member and spaced between the contacts, a movable contact member slidable on the tube, and means to connect the other stationary contact with the other terminal.

3. A circuit breaker comprising an elongated insulating member having a terminal at each end thereof, said member being hollow and having spaced contacts formed therein adjacent one end thereof, means to connect one of the contacts to the adjacent terminal, an insulating tube within the first member and spaced between the contacts, a movable contact member slidable on the tube, means to connect the other stationary contact with the other terminal, and means within the tube to urge the movable member into an open position.

4. A circuit breaker comprising an elongated insulating member having a terminal at each end thereof, said member being hollow and having spaced contacts formed therein adjacent one end thereof, means to connect one of the contacts to the adjacent terminal, an insulating tube within the first member and spaced between the contacts, a movable contact member slidable on the tube, means to connect the other stationary contact with the other terminal, means within the tube to urge the movable member into an open position, and cooperating splines and grooves formed in the tube and first named member.

5. A circuit breaker comprising an elongated insulating member having a terminal at each end thereof, said member being hollow and having spaced contacts formed therein adjacent one end thereof, means to connect one of the contacts to the adjacent terminal, an insulating tube within the first member and spaced between the contacts, a movable contact member slidable on the tube, means to connect the other stationary contact with the other terminal, means within the tube to urge the movable member into an open position, splines on the first named member forming diametrically spaced side grooves in which the stationary contacts are positioned, and extensions on the movable contact member received within the said grooves and formed with 50 contacting portions engaging the stationary contacts therein.

6. A circuit breaker comprising an elongated insulating member having a terminal at each end thereof, said member being hollow and having spaced contacts formed therein adjacent one end thereof, means to connect one of the contacts to the adjacent terminal, an insulating tube within the first member and spaced between the contacts, a movable contact member slidable on the tube, means to connect the other stationary contact with the other terminal, a disc slidable within the hollow tube and connected to the movable contact member, and a spring in the tube engaging the disc to urge the contact member into an open position.

7. A circuit breaker comprising spaced stationary breaker contacts, a movable member having contact portions engaging the respective stationary contacts, means to urge the movable member into an open position, bimetal means to hold the movable member in a closed position, manually operable means to move the movable member into engagement with the bimetal means, and means to close an electrical circuit between

the stationary contacts subsequent to the said engagement.

8. A circuit breaker comprising spaced stationary breaker contacts, a movable member having contact portions engaging the respective stationary contacts, means to urge the movable member into an open position, bimetal means to hold the movable member in a closed position, manually operable means to move the movable member into engagement with the bimetal 10 means, and means on the manually operable means to close an electrical circuit between the stationary contacts subsequent to the said engagement.

9. A circuit breaker comprising spaced stationary breaker contacts, a movable member having contact portions engaging the respective stationary contacts, means to urge the movable member into an open position, bimetal means to hold the movable member in a closed position, manually operable means to move the movable member into engagement with the bimetal means, and means on the manually operable means to connect the bimetal means electrically to one of the contacts after the said engagement. 15

10. A circuit breaker comprising an elongated member having a terminal at each end thereof, spaced stationary breaker contacts adjacent one end thereof, means to connect one of said contacts to the adjacent terminal, a movable contact member, means to urge the movable member into an open position, bimetal means connected to the other stationary contact to hold the movable member releasably in a closed position, a manually operable member to move the 35 movable member into circuit closing position, and means on the manual member to connect the bimetal means to the other terminal after the movable member is engaged by the bimetal means. 40

11. A circuit breaker comprising an elongated member having a terminal at each end thereof, spaced stationary breaker contacts adjacent one end thereof, means to connect one of said contacts to the adjacent terminal, a movable contact member, means to urge the movable member into an open position, bimetal means connected to the other stationary contact to hold the movable member releasably in a closed position, a manually operable member to move the movable member into circuit closing position, means to disengage the manually operable member from the movable member after engagement of the said movable member by the bimetal means, and means on the manual member to connect the bimetal means to the other terminal after the manual member has been disengaged from the movable member. 45 50 55

12. A circuit breaker comprising an elongated member formed with a central hollow portion and a hollow portion above the central portion, a terminal at each end of the elongated member, spaced stationary breaker contacts adjacent one end of the elongated member, means to connect one of the stationary contacts to the adjacent terminal, a movable contact member slidably mounted in the central hollow portion of the elongated member, means to urge the movable member into an open position, manually operable means slidable in the second hollow portion to move the movable member into closed position, and means in the last named hollow portion to release the movable member. 60 65 70
